(57) **CLAIM**

The ornamental design for a saliva collection vial, as shown and described.

DESCRIPTION

FIG. 1 is a top side perspective view of the saliva collection vial;

FIG. 2 is a bottom side perspective view of the saliva collection vial of FIG. 1;

FIG. 3 is a perspective view of the saliva collection vial of FIG. 1;

FIGS. 4, 5, and 6 are the same as FIGS. 1, 2, and 3, respectively, shown with a cap secured to top of the saliva collection vial;

FIG. 7 is a right-side view of the saliva collection vial of FIG. 1;

FIG. 8 is a left-side view of the saliva collection vial of FIG. 1; and,

FIG. 9 is a front-side view of the saliva collection vial of FIG. 1.

The broken lines depict environmental structure for illustrative purposes only and form no part of the claimed design.
